DESIGN FOR A COMBINED MOTOR AND BLOWER HOUSING FOR FUR BEATERS

Allen Trask, St. Paul, Minn., assignor to Walter
Haertel Products Co., Minneapolis, Minn., a cor-
poration of Minnesota

Application February 19, 1940, Serial No. 90,351

Term of patent 7 years

To all whom it may concern:

Be it known that I, Allen Trask, a citizen of the United States and residing in the city of St. Paul, county of Ramsey and State of Minnesota, have invented a new, original, and ornamental Design for a Combined Motor and Blower Housing for Fur Beaters, of which the following is a specification, reference being had to the accompanying drawing forming a part thereof, wherein,

Fig. 1 is a perspective view of a combined motor and blower housing for fur beaters showing my new design;

Fig. 2 is an elevational view of one side thereof;

Fig. 3 is an elevational view of the other side; and

Fig. 4 is a front elevational view thereof.

The dominant features of my design reside in the portions shown in full lines.

I claim:

The ornamental design for a combined motor and blower housing for fur beaters, as shown and described.

ALLEN TRASK.
